UNITED STATES PATENT OFFICE.

GEORGE F. MUTH, OF PHILADELPHIA, PENNSYLVANIA, ASSIGNOR TO NEWTON
MACHINE TOOL WORKS, INCORPORATED, OF PHILADELPHIA, PENNSYLVANIA,
A CORPORATION OF PENNSYLVANIA.

TOOL-HEAD FOR SLOTTING-MACHINES.

1,401,718.

Specification of Letters Patent. Patented Dec. 27, 1921.

Application filed March 1, 1920. Serial No. 362,592.

To all whom it may concern:

Be it known that I, GEORGE F. MUTH, a citizen of the United States, residing in Philadelphia, Pennsylvania, have invented 5 certain Improvements in Tool-Heads for Slotting-Machines, of which the following is a specification.

My invention relates to certain improvements in the construction of tool heads for 10 slotting machines.

One object of the invention is to construct the head so that the tool will be relieved on the upward stroke of the slide.

A further object of the invention is to provide 15 a head which can be turned on the slide so as to cut the front, rear, or either side of the slide.

In the accompanying drawings:

Figure 1 is a side view of sufficient of a 20 slotting machine to illustrate my invention;

Fig. 2 is a front view of the tool head and the lower portion of the slide;

Fig. 3 is a longitudinal sectional view on the line 3—3, Fig. 2;

Fig. 4 is a sectional view on the line 4—4, 25 Fig. 3;

Fig. 5 is a sectional view on the line 5—5, Fig. 3; and

Fig. 6 is a sectional view on the line 6—6, 30 Fig. 4.

1 is sufficient of the base of the machine to illustrate my invention. 2 is a portion of the standard having a slideway 3 for the ram 4, which has a rack 5 meshing with a 35 pinion of the ordinary type, 6 is a work carrying table. 7 is a slide of any usual form mounted on the base and supporting the table. My invention relates particularly to the tool carrying head, which is secured to 40 the lower portion of the ram 4, which is recessed to receive a block 8, held in place in the recess by a headed screw 9.

10 is a tool carrying head mounted on the under side of the ram and secured thereto, in 45 the present instance, by means of three bolts 11 having heads 12 adapted to the annular undercut channel 13 formed partly by a recess in the ram 4 and the stepped block 8, shown clearly in Fig. 3. The bolts 11 pass 50 through the upper portion of the tool carrying head 10 and into the recess 14, Fig. 5, in the head. In these recesses are washers 15 and nuts 16 so that the head, while it is free to turn on the ram, is held firmly against

the ram and can be locked in position by 55 screwing up the nuts 16. On the head is an annular rib 10^a which is adapted to the annular slot, through which the bolt 11 extends. This rib centers the carrying head. When it is desired to turn the head, all that is necessary is to back off the nuts and adjust the head to the point desired. In the under side of the head are two extensions 17 spaced apart and between these extensions is located 60 the tool holder 18. A tapered pivot pin 19 connects this tool holder with the head and forms a pivot on which it can turn.

In order to retain this tool holder yielding 65 against the under side of the head 10, I recess the head, as at 20, and locate a coiled 70 spring 21 in this recess. 22 is a bolt having a head 23 resting on the spring. The threaded portion 24 of the bolt is screwed into the tool holder 18, as shown clearly in Fig. 3. By this construction, the carrier will yield when 75 the ram is moved upward and will be held rigidly in position when the ram is moved downward. The holder has a perforated extension 25 for the reception of the tool, as shown in Fig. 1, and the tool is clamped to 80 the holder by bolts 26.

By the above construction, it will be seen 85 that the head can be turned on its pivot by loosening the nuts 16 so that it will cut at the front of the ram or at either side thereof. in fact at any point within the 360 deg. radius. The tool holder will yield as the tool returns from making the cut so that the machine can be used for cutting certain 90 surfaces in the work without the necessity of resetting the work as is now necessary.

I claim:

1. The combination in a slotting machine, 95 of a ram having an annular undercut slot in its under side; a head resting against the lower end of the ram; bolts having heads adapted to the annular slot and carried by the head so that the head can be clamped to the ram in any position desired; a tool holder pivoted to the head; and yielding means for 100 holding the tool holder to the head.

2. The combination of a ram recessed on its under side and having an annular groove therein; a stepped block mounted in the recess and forming with the groove in the ram 105 an annular undercut slot; a bolt holding the block in position in the slide; a head fitting against the slide; headed bolts passing

through openings in the head, the heads of the bolts extending into the annular, undercut slot, the head being recessed at the bolts for the reception of the nuts; a tool holder 5 pivotally mounted on the head; and yielding means for retaining the holder against the head.

3. The combination of a ram; a head mounted on the underside of the ram; bolts 10 securing the head to the ram; means for

allowing the head to turn on the ram when the bolts are slack; a tool holder pivoted to the head, the head being recessed at the opposite side from the pivot; a spring in the recess; and a headed bolt extending through the spring and screwed into the holder the head of the bolt bearing upon the spring so that the holder is allowed to yield when the tool is returning after making a cut. 15

GEORGE F. MUTH.
